BRAKE BEAM BALANCING DEVICE

Filed March 12, 1943

A device for balancing the weight of a railroad car's brake beam, which device is applied to the beam between the center hanger support and the end of the beam, and which device is formed of a flat strip of metal having a central bowed portion and two loops extending from the ends of the strip, the loops being disposed in the same direction to provide loops which extend beyond the plane of the intermediate bowed portion.

BRAKE BEAM BALANCING DEVICE

Malcolm S. Johnson, Chicago, Ill., assignor to Illinois Railway Equipment Company, Chicago, Ill., a corporation of Illinois

Application March 12, 1943, Serial No. 478,958

3 Claims. (Cl. 188—212)

My invention relates to a device whereby the brake beam of a railroad car brake system will be balanced and rotative tendency or movement of the brake beam eliminated and the tilting of the brake head, whereby the tip of the attached shoe is brought into contact with the car-wheel, will be prevented.

The present day brake beams, when assembled in the truck, are not balanced about the hanger bearing support in the brake head, due to the uneven distribution of weight about the hanger bearing resulting from such attachments as brake shoes, live or dead levers, dead lever guide, lever connecting rod, etc. of the brake rigging, with the result that excessive weight is produced on the tension side of the beam, causing the beam, when the brakes are in released position, to rotate to an extent which permits the top of the brake shoe to make contact with the car wheel.

A result of the condition mentioned, with the brake shoe continuously riding on the wheel when the brakes are in released position, naturally produces undue and wasteful wear of the shoes and wheels. The constant contact of the top of the shoe with the revolving car wheel causes the shoe to wear unevenly, with greater wear toward the top and prevents the maximum wear limits throughout the entire length of the shoe to be obtained, necessitating discarding of the shoe and producing waste and expense.

My improved balancer device prevents the usual jiggle or vibration between the hanger and the brake head as well as the resultant chatter and noise and consequent wear; the device maintaining a tighter relation between the hanger and the head, as well as maintaining a proper or uniform spaced relation between the entire shoe and the car wheel.

My improved device, which involves a resilient element, also tends to aid in brake release, especially after the car has become stationary; the device being suitable for all beams with brake heads hung from the center hanger location, with its application such that it cannot become displaced even though the brake shoe and its key are lost; the device being made of resilient metal in order to compensate for the change in relationship between the hanger and the brake head from a released position to a brake applied position.

The objects and advantages of my invention will be readily comprehended from the detailed description of the accompanying drawing wherein—

Figure 1 is a perspective view of my improved device.

Figure 2 illustrates my device applied to a brake head and hanger which are shown in side elevation with portions thereof and portions of a car-wheel broken away.

Figure 3 is a cross-sectional view taken substantially on the line 3—3 of Figure 2, with the brake applied condition shown in dotted lines.

My improved device is intended for use with the standard A. A. R. brake head and the drawing, Figure 2, shows its application to a center hung brake head 10, mounted on the end of the brake beam 11 and suspended by the hanger 12, whose upper end, broken away in the figure, is swingingly mounted in the usual hanger bracket 13 secured to the truck side frame of which a portion is shown at 13.

The brake head is provided with the usual top and bottom shoe bearing surfaces 14, 15 and the intermediate, vertically spaced lugs 16, which provide a shoe lug receiving socket therebetween. These lugs 16 have vertical openings extending therethrough to receive the usual vertically disposed key 17 which also passes through an opening or slot in the head tip 14 and through an opening in the lug 18 formed integral with the rear side of the brake shoe 19, thereby removably locking the shoe 19 to the head 10, with the weight and thrusts of the shoe transmitted to the upper end of the head and to the lower lug of the pair 16.

Due to the arrangement and mounting of the brake rigging an uneven distribution of weight about the hanger bearing maintains, produced by the brake shoes, the levers, the lever guide and lever connection rod, as previously stated; and this excessive overbalance induces rotative movement of the beam about its axis when the brakes are in released position, the rotative movement of the beam being in a direction toward the car wheels and hence causing the brake head at its upper end to tilt toward the car wheel.

In order to resist the overturning or rotative action of the beam and the consequent tilting of the brake head, I have devised my improved balancer 20 shown in perspective in Figure 1, formed from a flat strip of spring steel of predetermined thickness, width and length and possessing sufficient strength to resist the overturning action of the beam. The flat bar or strip is bent into sinuous form or double ogee curvature with the ends 21, 21 of the strip of equal length and disposed in the same direction to provide the loops 22, 22 which extend beyond the plane of the intermediate bowed head engaging portion 23.

which is spaced from the end loops 22, 22' by the curved and flexing portions 24, 24'.

The device 20 is arranged transversely of the brake head so as to be disposed between the shoe locking key 17 and the rearwardly curved or recessed intermediate portion of the brake head 10 at a point above the upper lug 16, while the loops 22, 22', extend rearwardly at opposite sides of the head and about the two legs or sides 12^a of the hanger 12, as shown in Figure 3.

When the device and the brake members are in complete assembled position, the central bowed portion 23 bears against the forward face of the brake head and resists the opposite pull exerted by the ends disposed about what may be termed the rear sides of the hanger 12.

In order to apply or to remove the device, the brake hanger must be removed from the hanger bracket on the side frame of the truck and the brake shoe and key must also be removed. The device is then placed in the recessed forward face of the brake head above the upper lug 16, with the convex surface of the bowed portion 23 against the brake head, and the two sides or legs of the hanger 12 arranged in the end loops 22, 22' and the upper end of the hanger then inserted in the hanger bracket. The shoe 19 is then applied with its lug 18 disposed between the lugs 16, 16' of the brake head thereby bringing the openings through the lugs into register for insertion of the locking key 17. The device is so formed that when the assembly has been made, the device will exert rearward pressure on the brake head and thereby prevent the usual forward rotative movement of the brake beam 11 resulting from the unbalanced condition produced by the various levers heretofore mentioned and the brake heads with their attached shoes.

The device preferably is made of a flat strip or bar of spring steel, instead of round material, to provide a wider bearing on the head and hanger; and in order to prevent the side edges of the device digging into the brake head and the hanger and causing undue wear, the head engaging portion 23, as well as the hanger receiving loops 22, are slightly dished transversely to present a convexed surface, respectively, against the head and also against the hangers as indicated at 23^a and at 22^a, 22^a.

I have shown and described what I believe to be the best embodiment of my invention, but

certain structural modifications are possible without, however, departing from the spirit of my invention as defined in the appended claims.

What I claim is:

5. A brake beam balancing device comprising, in combination with the brake beam of a railroad car having a brake head mounted thereon and a link hanger whereby the head is pendently supported from the car truck frame, a resilient wide bar of sinuous form intermediate its ends to provide a rearwardly curved brake head engaging portion, the portions at either side of the head engaging portion being bent rearwardly beyond the same side of the brake head engaging portion and formed into forwardly facing hook portions, said bar being disposed transversely of the brake head with the intermediate curved portion engaging the forward face of the brake head and the hook portions engaging the rearward sides of the link hanger.
10. 2. In a brake beam balancing device of the character described, the combination of a brake head, a link hanger for pendently supporting the brake head from the car truck frame of a railroad car, and a resilient bar, disposed transversely of the brake head, provided with a sinuous intermediate portion involving a rearwardly curved part bearing against the forward face of the brake head in a plane above the pivotal connection between the brake head and hanger, while the ends of said bar curve rearwardly of the brake head engaging portion and terminate in forwardly facing hook portions arranged rearward of the link hanger.
15. 3. In a brake beam balancing device of the character described, the combination of a railroad car brake head, a link hanger whereby the brake head is pendently supported from the car truck frame, and a resilient bar provided with a sinuous intermediate portion involving a rearwardly curved part, said bar being disposed transversely of the forward face of the brake head with said curved part bearing against the forward face of the brake head in a plane above that of the pivotal connection between the brake head and the hanger, with the ends of said bar curved rearwardly of the brake head and hooked about the rear of the link hanger, the brake head and link hanger engaging portions of the bar being of comparative width and convexed transversely.

MALCOLM S. JOHNSON.
